(57) **CLAIM**

The ornamental design for a vehicle-wheel front face, as shown and described.

DESCRIPTION

FIG. 1 is a perspective view of a vehicle-wheel front face according to my new design;

FIG. 2 is a front elevational view thereof; and,

FIG. 3 is a side elevational view thereof, taken from the left side of FIG. 2.

Portions of the wheel depicted in broken line are for illustrative purposes only, and form no part of the claimed design.
